AARON L. VAN EMDEN, OF TURTLE CREEK, PENNSYLVANIA, ASSIGNOR TO WESTINGHOUSE ELECTRIC & MANUFACTURING COMPANY, A CORPORATION OF PENNSYLVANIA

BUS LINE JUMPER CONNECTER

Application filed April 11, 1929. Serial No. 354,285.

My invention relates generally to connectors for current conductors and more particularly, to plug connectors or jumper heads of the protected type for bus or train-line jumpers.

The object of my invention, generally stated, is to provide plug-type connectors for bus-line jumpers that shall be simple in construction and economical to manufacture.

10 A more specific object of my invention is to provide a bus-line connector having an arc protector which is retained in engagement with the face of a receptacle until the contact members of the connector and the receptacle have been disengaged.

15 A further object of my invention is to provide for maintaining an arc shield around the terminal members of a plug connector until the connector has been withdrawn from the receptacle a sufficient distance to disengage the connector terminals from the terminals of the receptacle.

20 Another object of my invention is to provide for confining the current arc which may be drawn between the cooperating contact members of a plug connector and a bus-line receptacle when they are disengaged.

25 Other objects of the invention will become evident from the following description, taken in conjunction with the drawing, in which,

30 Figure 1 is a sectional view, taken along the longitudinal axis of a preferred form of my invention showing a plug connector, having a spring-biased protector inserted within a bus-line receptacle;

35 Fig. 2 is a view, in longitudinal section, of a modified form of my plug connector, having a sleeve-type protector disposed to be operated when a connection is being broken;

40 Fig. 3 is a sectional view, taken along the line III-III of Fig. 2, showing details of a locking ring provided with operating members which may be actuated when the jumper head and receptacle are moved relative to each other, and

Fig. 4 is a cross-sectional view, taken along the line IV-IV of Fig. 1, showing the position of the protector with respect to the contact members of the connector, when the jumper head is in the receptacle.

45 Fig. 5 is a view, taken along the line V-V of Fig. 3, showing the construction of the beveled slots located in the tubular end portion of the plug connector.

50 Referring now to Fig. 1 of the drawing, 10 designates, generally, a connecting device suitable for coupling bus-line jumpers between the cars of an electric train. In this particular form of construction, the connecting device 10, comprises a plug-type connector, or jumper head 11, and a receptacle 12. The receptacle 12 forms no part of the present invention, but is illustrated merely to show, in a better way, the features of the plug connector. The receptacle shown is representative of the form in common use, being adapted for mounting on a car or other vehicle.

55 As shown, the receptacle 12 comprises a base or body member 13, having an extended sleeve portion 14 provided with an insulating lining 15, which forms a receiving chamber for the plug connector 11. It is also provided with a contact-terminal member comprising a contact support 16 and a plurality of contact studs or fingers 17. The 60 contact-terminal member may be retained in its proper position within the body member of the receptacle by means of a sleeve-support member 18 of suitable insulating material, and fiber locking pins 19 which prevent longitudinal movement of the contact-terminal member with respect to the body member 13.

65 As shown, the receptacle is further provided with a cover 20, that is disposed to receive the conductor cable 21 which may be connected to the contact support 16 in any well known manner.

70 The plug connector 11 may be of any desired shape, suitable to be utilized with a

standard-type bus-line receptacle, such as shown generally at 12 and described hereinbefore. In this embodiment of the invention, the plug connector, in the preferred form, comprises a body member 22 provided with a handle portion 23 and a tubular end portion 24 that may readily be inserted into the receiving chamber formed by the extended sleeve portion 14 of the 10 receptacle 12.

As shown, the plug connector is provided with a contact-support member 25 having contact or socket members 26 which are adapted to receive the contact studs, or 15 fingers 17, of the receptacle 12. In this embodiment of the invention, the contact-support member 25 is carried within an insulating sleeve 27 which is mounted within the tubular end portion 24 of the body member 20 22, as shown.

In order to provide for connecting the 25 socket members 26 to a bus-line jumper, comprising a conductor 28, the handle portion 23 is provided with an opening which communicates with the tubular end portion 24 of the connector and through which the current conductor or cable may extend. The 30 end of the cable 28 is connected to the contact-support member 25 in any suitable manner and may be further secured in position by utilizing an insulating compound 29 which may be introduced into the hollow interior of the body member 22, through an 35 opening 31 which is closed by a pipe plug 32.

In the use of bus-line connectors of this 40 type, it is often required that the plug connector shall be removed from the receptacle when the bus-line is energized by a comparatively high voltage, i. e., the bus line may still be connected to the trolley or other 45 source of supply for operating the train. Therefore, it will be evident that the operator, in removing the plug connector from the receptacle, may be endangered from current arcs which are drawn between the disengaging contact members of the plug connector and the receptacle. Since the body member of the plug connector is usually of 50 metallic nature, it will be evident that an arc may jump from the contact terminals of the receptacle to the tip of the tubular sleeve portion 24 before the contact members have parted a sufficient distance to extinguish the 55 main arc.

As shown in the drawing, when the plug connector is inserted into the receptacle until the contact members 17 and 26 become engaged, there is only a short distance between 60 the ends of the contact fingers 17 and the tip of the tubular end portion 24, with only a comparatively thin insulator, comprising the sleeve 27, interposed between these two members, to prevent the establishment of a 65 current arc between any one of the contact

fingers 17 and the tip of the tubular end portion 24.

With a view to providing a more effective protector between the contact terminals 17 and the tip of the tubular end portion 24, 70 provision is made for maintaining an arc shield between these members until the contact members 26 and 17 have become completely disengaged and parted a sufficient distance to extinguish the arc which may be 75 drawn.

In this particular embodiment of the invention, the arc protector comprises a sleeve 80 35, of insulating material, carried within an annular channel formed by the insulating sleeve 27 and the inside surface of the tubular end portion 24. The protector sleeve 35 is disposed for movement relative to the contact members 26 of the plug connector 11. In order to limit the longitudinal movement of the sleeve member 35, stop members 36 are provided which are disposed to engage in slots 37 in the sleeve member 35. In this instance, the stop members 36 are secured in the desired position on the tubular-sleeve 90 portion 24 by means of screws 38, thereby providing definite limits of travel for the protective sleeve 35.

It will be readily understood that, in order 95 for the protector sleeve 35 to be effective when the contact members of the plug connector and the receptacle are disengaged, means must be provided for retaining the end portion or tip 39, of the protector sleeve in engagement with the face portion 40 of the receptacle, as shown. Therefore, in this embodiment of the invention, a suitable coil spring 41 is placed within the annular channel in a position to bias the protector sleeve 35 outwardly to cause it to extend a considerable distance beyond the contact sockets 26 of the plug connector. 100

Therefore, it will be evident that when the plug connector is inserted into the receptacle, with the end of the sleeve protector 35 biased to the outer position, the tip 39 of the latter will engage the face 40, of the receptacle 12 before the respective contact members 26 and 17 engage, and is retained in engagement by means of the spring 41 until the plug is withdrawn from the receptacle to break a circuit connection. 110

It is evident that the greatest danger lies in the establishment of a current arc between the energized contact fingers of the receptacle and the body member of the plug connector when the latter is removed from a live or energized receptacle. Since the tip 39 of the protector sleeve 35 is biased into engagement with the face portion 40 of the receptacle 12, an arc shield is automatically maintained between the terminal member 17 and the tip of the tubular portion 24, until the circuit is broken. Since the length of the slots 37 in the protector sleeve 35, controls 120 125 130

the degree of relative movement between the protector sleeve 35 and the body member of the plug connector, the distance interposed between the contact members before the arc shield is broken, may be varied by changing the length of the slots 37.

The plug connector 11 may be locked within the receptacle 12 in any suitable manner. However, in this embodiment of the invention, the receptacle 12 is provided with a lid 42, hingedly secured to the base member 13, and provided with a projection 43 on the inner side, which is disposed to engage a similar projection 44 on the body member of the plug connector 11. It will be readily understood that the lid 42 must be raised in order to admit the plug connector and to release it after it has once been locked in position.

In the preferred form of my invention, which has been described in detail hereinbefore, the projector sleeve, which engages the face of the receptacle to provide an arc-box during the insertion and withdrawal of the plug connector, is automatically controlled by means of a coil spring which permits the protector sleeve to function in a desired manner whenever the plug connector is inserted within the receptacle. However, this same principle of protection may be provided by utilizing a protector sleeve which is mechanically controlled.

In Figs. 2 and 3 of the drawing, is shown a plug connector provided with a protector sleeve and a suitable mechanical device for controlling the operation of the sleeve. Since the plug connector, in this instance, is essentially the same as that shown in Fig. 1, and described in detail hereinbefore, with the exception that the actuating spring 41 for the protector sleeve is not shown, the parts in Figs. 2 and 3, similar to those in Fig. 1 will be designated by the same reference numerals.

When it is desired to use a plug connector of this type, a suitable locking ring, shown generally at 46, may be utilized for retaining the plug connector in a receptacle, and having means provided thereon for mechanically controlling the operation of the protector sleeve.

In this embodiment of the invention, the locking ring 46 is rotatably mounted upon the sleeve-end portion 14 of the receptacle 12 in such manner that, when it is rotated through a predetermined angle, it will release the plug connector from the receptacle and mechanically lock the protector sleeve into a position to engage the face of the receptacle in the same manner as if it were controlled by means of a biasing spring. In this view, for the sake of simplifying the drawing, a major portion of the receptacle has been omitted, since it is shown in detail in Fig. 1.

In order to lock the plug connector within the receptacle 12, the locking ring 46 is provided with a lug 47, which, when the handle

of the locking ring is moved to the vertical position, moves in front of the projection 48, on the body member of the plug connector, and retains it in position.

Since the protector sleeve 35 is loosely carried by the plug connector, it will be readily understood that, when the plug connector is inserted within the receptacle, the tip 39 of the sleeve is actuated into engagement with its face 40. In order to retain the protector sleeve in this position until the plug connector is withdrawn a sufficient distance to effect the disengagement of the contact members, provision is made for mechanically locking the protector sleeve in response to the movement of the locking ring to a releasing position.

Any suitable kind of locking mechanism may be utilized for this purpose. However, in this embodiment of the invention, a plurality of locking members 49, provided with locking pins 50, are pivotally mounted upon the face of the locking ring 46, as shown.

Referring particularly to Fig. 3, the locking members 49 are shown in full lines in their released positions and in dotted lines in their engaging positions. The locking members 49 are held in their disengaged positions against the force of their actuating springs 51, since the locking pins 50 bear directly upon the outside surface of the tubular sleeve portion 24 of the plug connector 11.

In order to cause the locking pins 50 to engage the protector sleeve 35 to retain its tip 39 in engagement with the face portion 40 of the receptacle when the plug connector is removed, a plurality of longitudinal beveled slots 52 are provided in the tubular end portion 24, which permit the locking pins 50 to extend into the annular chamber directly back of the protector sleeve 35, when the locking ring is moved to a releasing position, as shown. The beveled slots 52 in the tubular sleeve portion 24 of the plug connector permit the plug connector to be withdrawn a distance equal to the length of the slots 52 while the protector sleeve is retained by the locking pins 50.

When the plug 11 is withdrawn from the receptacle 12 to a distance equal to the length of the slots 52, it will be readily understood that the locking pins 50 will be actuated out of engagement with the protector sleeve 35 because of the beveling of the edges of the slots 52, and will move along the outer surface of the tubular end portion 24. On further outward movement, the stop members 36 will engage the sleeve member 35 at the rear end of the slots 37, thereby permitting the complete withdrawal of the plug 10. As described hereinbefore, the protector sleeve 35 will remain in engagement with the receptacle 10 for a sufficiently long time to prevent arcing between the energized contact fingers 17 and the body member of the plug 11, when

the latter is removed from an energized receptacle.

Therefore, the operation of the protector sleeve may be effectively controlled by means of a biasing spring or by means of suitable devices carried by a locking ring of the receptacle.

Since certain changes may be made in the above construction, and different embodiments of the invention may be made without departing from the spirit thereof, it is intended that all matter contained in the above description, or shown in the accompanying drawing, shall be interpreted as illustrative and not in a limiting sense.

I claim as my invention:

1. In a bus-line connector, in combination, a hollow body member adapted to be inserted in a receptacle, a conductor carried by the body member, a contact-terminal member carried in the end of the body member having its contact terminals connected to the conductor, means inserted within said hollow body member to provide an annular recess extending longitudinally to the end portion which carries the contact terminal member adapted to receive a sleeve member, and a sleeve of insulating material carried in said annular recess, said sleeve being movable relative to the end of the contact-terminal member to prevent the establishment of an arc from the body member to energized contact terminals and to enclose arcs drawn between said terminals when the connector is withdrawn from a receptacle.

2. In a cable connector comprising, in combination, a receptacle disposed to be attached to one end of the cable, said receptacle having a face portion with contact members protruding therefrom, and a sleeve portion enclosing the contact members, a plug member disposed to be attached to the end of another cable, said plug being disposed to enter the sleeve portion when the contact members are engaged, and a spring-biased sleeve member of insulating material carried by the plug member disposed to extend beyond the contact members to engage the face of the receptacle, thereby to provide means for confining an arc which may be drawn between the contact members when the plug is inserted or removed from the receptacle.

3. In a bus-line connector, in combination, a receptacle, a terminal member located in said receptacle, a plug adapted to operatively engage the receptacle and provided with a pair of spaced cylinders forming an annular recess therebetween, a conductor located within the inner of said cylinders, a contact member disposed to engage said terminal member, said contact member also being located within the inner cylinder and connected to said conductor, an insulating sleeve slidably mounted in said annular recess and disposed to engage said receptacle when the plug is in

operative engagement therewith, and means disposed to cooperate with said sleeve for maintaining it in engagement with said receptacle until the plug is withdrawn therefrom to a predetermined distance.

4. In a bus-line connector, in combination, a receptacle, a terminal member located in said receptacle, a plug adapted to operatively engage the receptacle and provided with a pair of spaced cylinders forming an annular recess therebetween, a conductor located within the inner of said cylinders, a contact member disposed to engage said terminal member, said contact member also being located within the inner cylinder and connected to said conductor, an insulating sleeve slidably mounted in said annular recess and disposed to engage said receptacle when the plug is in operative engagement therewith, and a resilient member mounted in said annular recess and adapted to cooperate with the plug to bias the sleeve into engagement with the receptacle until the plug is withdrawn therefrom to a predetermined distance.

5. In a connecting device, the combination with a receptacle provided with a terminal member and a plug also provided with a terminal member and disposed to engage the receptacle to provide electrical contact between the terminal members, of a slotted cylindrical arc shield slidably mounted on said plug, a plurality of stop members mounted on said plug and in the slots of said shield for limiting the movement thereof and a resilient member mounted on said plug and disposed to bias said shield to a predetermined position.

6. In a bus-line connector, in combination, a hollow body member adapted to be inserted in a receptacle, a conductor carried by the body member, a contact-terminal member carried in the end of the body member having its contact terminals connected to the conductor, means inserted within said hollow body member to provide an annular recess extending longitudinally to the end portion which carries the contact terminal member and adapted to receive a sleeve member, a sleeve of insulating material slidably mounted in said annular recess and disposed to engage said receptacle, and means mounted on said receptacle and disposed to cooperate with said sleeve to maintain it in engagement with said receptacle until the terminal member is withdrawn therefrom to a predetermined distance.

7. In a connecting device, the combination with a receptacle provided with a terminal member and a plug also provided with a terminal member and disposed to engage the receptacle to provide electrical contact between the terminal members, of a locking member mounted on said plug, a rotary locking lever mounted on said receptacle and disposed to cooperate with said locking member to maintain engagement between the plug

and the receptacle, a slotted cylindrical arc
shield slidably mounted on said plug and dis-
posed to engage said receptacle, a plurality
of stop members mounted on said plug and
in the slots of said shield for limiting the
movement thereof, and a plurality of resili-
ently biased clamping members mounted on
said locking lever and disposed to maintain
said arc shield in engagement with said re-
ceptacle when the locking lever is moved to
the unlocked position until the plug is with-
drawn to a predetermined distance.

In testimony whereof, I have hereunto sub-
scribed my name this 2nd day of April 1929.
